UNITED STATES PATENT OFFICE

WILLIAM F. HENDERSON, OF COLFAX, WASHINGTON

WRECKER BAR

Application filed September 10, 1929. Serial No. 391,615.

My invention relates to wrecker bars and certain objects of the invention are to provide a wrecker bar having a carriage member with a wheel for a purchase whereby the claw end 5 of the bar may be slidably moved under a nail head or the like while it is being drawn and thus raise the nail in a substantially straight line rather than in the arc of a circle which has heretofore caused binding and 10 bending of the nail while it is being withdrawn. Further objects of the invention are to provide adjustable means for the carriage member whereby the length of purchase of the bar may be increased or decreased as 15 desired.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

Figure 1 is a view in perspective showing 25 the application of the wrecker bar in removing a nail;

Fig. 2 is a view in side elevation of a portion of the device and showing the adjusted position of the carriage member in dotted lines for increasing the length of purchase;

Fig. 3 is a view in transverse section through the carriage member taken substantially on a broken line 3, 3 of Fig. 2; and

Fig. 4 is a similar view taken on a broken 55 line 4, 4 of Fig. 2.

Referring to the drawings throughout which like reference numerals designate like parts, the numeral 5 indicates the main body portion of the wrecker bar which is provided at one of its ends with a claw portion 6 and at its other end with a chisel portion 7. Said body portion is offset a short distance from the chisel end to form a shoulder 8 which may be used to hammer against when driving the claw under a nail head as will be understood.

A carriage member 9 is fitted over the bar 5 and pivotally secured thereto by a bolt or rivet 10 at a short distance from the claw 50 end of said bar member. A wheel 11 is

mounted to revolve within the carriage member as clearly shown in the drawings.

The wheel 11 provides anti-friction purchase means whereby the claw 6 may be easily moved under the head of a nail and whereby 55 the device may be manipulated in such manner while the nail is being withdrawn that the nail may be raised straight out on its longitudinal axis as clearly shown in dotted lines in Fig. 1 of the drawings.

The means for adjusting the carriage member 9 for purchase, as most clearly shown in Fig. 2, comprises a plurality of holes 12 through the sides of the carriage member, and a hole 13 through the bar 5. Said carriage member may thus be pivotally moved on the pivot 10 until one of the holes through the carriage coincides with the hole through the bar and a split pin 14 or the like may be passed through said holes to retain the 70 carriage in the desired position. When said carriage is pivotally raised the length of purchase will be increased and when same is lowered the purchase will be decreased as will be understood.

It will now be apparent that I have provided a wrecker bar with anti-friction means whereby a nail may be drawn straight out and with adjustable means whereby the length of purchase for drawing nails may 80 be increased or decreased as desired.

Having thus described my invention, it being understood that minor changes may be resorted to in its construction without departing from its scope and spirit, what I 85 claim and desire to secure by Letters Patent of the United States is:

A wrecker bar comprising a main body portion having a claw at one end and an offset shoulder adjacent its other end, a carriage member pivotally mounted on said bar adjacent the claw end thereof, a wheel for said carriage member, and means whereby said carriage member may be adjusted to different pivotal positions.

In testimony whereof I affix my signature.
WILLIAM F. HENDERSON.
